CORNER GUARD FOR LUGGAGE

Walter Bialo, New Rochelle, N. Y.

Application March 24, 1952, Serial No. 19,033

Term of patent 7 years

(Cl. D87—1)

To all whom it may concern:

Be it known that I, Walter Bialo, a citizen of the United States of America, and a resident of the city of New Rochelle, in the county of Westchester and State of New York, have invented a new, original, and ornamental Design for a Corner Guard for Luggage, of which the following is a specification, reference being had to the accompanying drawing, forming a part thereof.

Fig. 1 is a perspective view of a corner guard for luggage showing my new design, and

Fig. 2 is an end elevational view of the corner guard shown in Fig. 1.

The broken line disclosure in the drawing is for illustrative purposes only.

I claim:

The ornamental design for a corner guard for luggage, substantially as shown and described.

WALTER BIALO.
